JOINT OR SEAM CONSTRUCTION FOR
DRIER FELTS AND THE LIKEJames K. Diamond, Grand Rapids, Mich., as
signor to Clipper Belt Lacer Company, Grand
Rapids, Mich.

Application May 26, 1933. Serial No. 673,003

9 Claims. (Cl. 24—33)

The main objects of this invention are to provide a joint or seam or coupling for drier felts, laundry ironing machine aprons and the like by means of which the ends of the felt or apron may be joined so that the strain upon the felt or apron is minimized and the pull thereon distributed over a substantial surface and, further, in a manner that permits the ready attachment of the joint members and in which they are so joined that the working surface is not obstructed.

A further object is to provide a structure having these advantages in which the joint members may be prepared in a factory equipped for that purpose and readily applied in a paper mill or laundry or other place of use.

Objects relating to details and economies of my invention will appear from the description to follow. The invention is defined and pointed out in the claims.

20 A structure which is a preferred embodiment of my invention is illustrated in the accompanying drawing, in which:

Fig. 1 is a fragmentary plan view of a drier felt embodying my improved joint or seam.

25 Fig. 2 is a fragmentary longitudinal section on a line corresponding to line 2—2 of Fig. 1.

Fig. 3 is a fragmentary perspective view of one of the seam or joint members.

Fig. 4 is a second perspective view further illustrating the joint member.

In the accompanying drawing, 1, 1 represent the parts to be joined, a drier felt being conventionally illustrated. There are two joint members for each joint but as these are duplicates, a 35 description of one will suffice.

The joint member or lacing unit comprises a strip of fabric 2, preferably a good quality of canvas, of a length corresponding to the width of the drier felt or other part to be joined. This 40 strip is folded upon itself, the edge portions of the strip providing attaching flaps 3 which are lapped upon the sides of the drier felt portion 1. A filler strip or filler 4 is arranged in the fold with its outer edge 5 in abutting engagement 45 with the bight 6 of the strip. This filler strip is of substantial width and is preferably arranged with its inner edge 7 in abutting engagement with the end of the felt, the filler strip being of less width than the folded fabric, as illustrated. The 50 filler strip and side portions of the fabric strip comprise the front portion of the lacing unit.

The filler strip is of fibrous material, preferably felt, although it may be of canvas or like material folded upon itself, and this is of substantial thickness so that the prongs 8 of the loop-like lacing

hooks or lacer elements 9 may be embedded therein. These lacing hooks 9 are of well-known type and they are arranged with their arms overlapping opposite sides of the folded strip 2 and their prongs embedded therein and in the filler strip 4.

I preferably provide a row of stitches 10 through the fabric and filler strip between the prongs and the edge of the fabric. This results in a very secure connection for the lacing hooks and the pull on the lacing hooks is not only sustained by the fabric 2 but by the filler and the pull on this filler is sustained by the bight of the fabric so that the seam members are capable of sustaining very heavy loads without tearing, or the hooks pulling out.

The flaps 3 are preferably attached by through stitches 11, the result being that a very secure attachment is had through the felt and one which distributes the pull thereon over a substantial area.

The two seam or joint members are arranged with their hooks in overlapping relation and coupled by the pivot or coupling pin 12. This pivot pin lies in the central plane of the parts joined and therefore the pull thereon is most effectively 80 positioned to prevent distortion and to secure the maximum strength.

The filler strip is of somewhat less thickness than the part to be joined so that the hooks or metal parts lie within the planes of the sides of the felt or other parts joined so that the work carried by the felts or aprons is not subjected to undue pressure at the joint. Flaps may be provided to cover the metal parts, if desired.

With this arrangement of parts, the seam members may be manufactured and the hooks applied in a factory equipped for the purpose and sent out in strips of considerable length to be cut to the desired size or length for the parts to be joined. This results in great economy both in 95 the manufacture and in the application of the joint.

I have not attempted to illustrate or describe various modifications or adaptations of my invention which I contemplate as it is believed that 100 this disclosure will enable those skilled in the art to embody or adapt my improvements as may be desired.

Having thus described my invention, what I claim as new and desire to secure by Letters Patent, is:

1. A drier felt joint comprising coacting joint members, each joint member comprising a strip of fabric folded upon itself and of a length approximating the width of the felt, a drier felt 110

portion disposed between the folded parts of the fabric, a filler strip of fibrous material and of substantial thickness disposed in the bight of the folded strip with its inner edge in abutting relation to the end of the felt portion, the filler strip being of less width than the folded fabric, the portions of the fabric projecting beyond the filler strip constituting securing flaps lapped upon opposite sides of the felt portion and secured thereto by through stitches, loop-like lacing hooks, the arms of which terminate in prongs engaging the joint member from opposite sides thereof and embedded in said filler strip, there being a row of stitches through the fabric and filler strip between the prongs of said lacing hooks and the bight edge of said joint member, the lacing hooks of the joint members being arranged in interlapping relation, and a coupling pin engaging the interlapped ends of said lacing hooks, the coupling pin being in the central longitudinal plane of the felt.

2. A drier felt joint comprising coacting joint members, each joint member comprising a strip of fabric folded upon itself, a drier felt portion disposed between the folded parts of the fabric, a filler strip of fibrous material and of substantial thickness disposed in the bight of the folded strip with its inner edge in abutting relation to the end of the felt portion, the filler strip being of less width than the folded fabric, the portions of the fabric projecting beyond the filler strip constituting securing flaps lapped upon opposite sides of the felt portion and secured thereto, loop-like lacing hooks, the arms of which terminate in prongs engaging the joint member from opposite sides thereof and embedded in said filler strip, the lacing hooks of the joint members being arranged in interlapping relation, and a coupling pin engaging the interlapped ends of said lacing hooks.

3. In a joint of the class described in combination with the parts to be joined, of joint members each comprising a strip of fabric folded upon itself, a filler strip of flexible material disposed in the folded strip with its outer edge in supporting engagement with the bight thereof, the filler strip being of less width than the folded fabric, the portions of the fabric projecting beyond the filler strip constituting securing flaps lapped upon opposite sides of a part to be joined and secured thereto by through stitches, loop-like lacing hooks, the arms of which terminate in prongs engaging the joint member from opposite sides thereof and embedded in said filler strip, there being a row of stitches through the fabric and filler strip between the prongs of said lacing hooks and the bight edge of said joint member, the lacing hooks of the joint members being arranged in interlapping relation, and a coupling pin engaging the interlapped ends of said lacing hooks.

4. In a joint of the class described in combination with the parts to be joined, of joint members each comprising an imperforate strip of fabric folded upon itself, a filler strip of flexible material disposed in the folded strip with its outer edge in supporting engagement with the bight thereof, the filler strip being of less width than the folded fabric, the portions of the fabric projecting beyond the filler strip constituting securing flaps lapped upon opposite sides of a part to be joined and secured thereto, loop-like lacing hooks, the arms of which terminate in prongs engaging the joint member from opposite sides thereof and

embedded in said filler strip, the prongs on the loop-like lacing hooks penetrating the folded over portions of the fabric as well as the filler strip, the lacing hooks of the joint members being arranged in interlapping relation, and a coupling pin engaging the interlapped ends of said lacing hooks.

5. A joint member for drier felts and the like comprising a strip of fabric folded upon itself and of a length approximating the width of the felt, a filler strip of fibrous material disposed in the bight of the folded joint with its outer edge in supporting engagement with the bight of the strip, the filler strip being of less width than the folded fabric, the portions of the fabric projecting beyond the filler strip constituting securing flaps, and loop-like lacing hooks, the arms of which terminate in prongs engaging the joint member from opposite sides thereof and embedded in said filler strip, there being a row of stitches through the fabric and filler strip between the prongs of said lacing hooks and the bight edge of said joint member.

6. A joint member for drier felts and the like comprising a strip of fabric folded upon itself and of a length approximating the width of the felt, a filler strip disposed in the bight of the folded joint with its outer edge in supporting engagement with the bight of the strip, the filler strip being of less width than the folded fabric, the portions of the fabric projecting beyond the filler strip constituting securing flaps, and loop-like lacing hooks, the arms of which terminate in prongs engaging the joint member from opposite sides thereof and embedded in said filler strip, the prongs on the loop-like lacing hooks penetrating the folded over portions of the fabric as well as the filler strip.

7. A lacing unit comprising a strip of fabric folded upon itself and adapted to overlap opposite sides of a drier felt or the like to be joined, a filler disposed in the fold of said strip between the edge of the felt and the bight of the strip, and a set of loop-like lacer elements having arms thereof overlapping opposite sides of said lacing unit and terminating in prongs embedded therein and engaging said filler, the prongs penetrating the folded over portions of the fabric as well as the filler, there being a row of stitches through the fabric and filler strip between the prongs and the fold of said lacing unit.

8. A lacing unit comprising a strip of fabric folded upon itself and adapted to overlap opposite sides of a drier felt or the like to be joined, a filler disposed in the fold of said strip between the edge of the felt and the bight or fold of the strip, and a set of loop-like lacer elements having arms thereof overlapping opposite sides of said lacing unit and terminating in prongs embedded therein and engaging said filler, the prongs penetrating the folded over portions of the fabric as well as the filler.

9. A lacing unit comprising a front portion of substantial thickness and a pair of flaps adapted to overlap opposite sides of a part to be joined for attachment to the front portion, the front portion including a filler of substantial thickness adapted to abut the edge of the part to be joined, and a set of loop-like lacer elements having arms thereof overlapping the opposite sides of the lacing unit and terminating in prongs embedded therein, the prongs penetrating the folded over portions of the fabric as well as the filler.

JAMES K. DIAMOND.
